The ornamental design for a table top support arm, as shown and described.

DESCRIPTION

FIG. 1 is a right side elevational view of a table top support arm showing our new design;

FIG. 2 is a front elevational view thereof;

FIG. 3 is a top plan view thereof;

FIG. 4 is a left side elevational view thereof;

FIG. 5 is a rear view in elevational thereof;

FIG. 6 is a bottom plan view thereof;

FIG. 7 is a top and side perspective view thereof; and,

FIG. 8 is a bottom and side perspective view thereof.

The broken lines shown in FIGS. 1-8 are environmental only and outline portions of our table top support arm which are hidden in normal use and therefore form no part of the claimed design. The solid jagged lines in FIG. 1-8 represent indefinite edges.
